(57) **CLAIM**

I claim the ornamental design for a device for grooming the coats of animals, as shown and described.

DESCRIPTION

FIG. 1 is a front perspective view of a device for grooming the coats of animals according to one implementation showing a handle in broken lines for context;

FIG. 2 is a rear perspective view of a device for grooming the coats of animals according to one implementation showing a handle in broken lines for context;

FIG. 3 is right side elevation view of a device for grooming the coats of animals according to one implementation showing a handle in broken lines for context;

FIG. 4 is left side elevation view of a device for grooming the coats of animals according to one implementation showing a handle in broken lines for context;

FIG. 5 is front side elevation view of a device for grooming the coats of animals according to one implementation showing a handle in broken lines for context;

FIG. 6 is rear side elevation view of a device for grooming the coats of animals according to one implementation showing a handle in broken lines for context;

FIG. 7 is top elevation view of a device for grooming the coats of animals according to one implementation showing blade containment apparatus in broken lines for context; and,

FIG. 8 is bottom elevation view of a device for grooming the coats of animals according to one implementation showing blade containment apparatus in broken lines for context.

The elements in broken line are not claimed.
